Patented May 13, 1919.

UNITED STATES PATENT OFFICE.

FRANK J. HUMMEL, OF PITTSBURGH, PENNSYLVANIA.

TOY RAILWAY.

1,303,668.

Specification of Letters Patent. Patented May 13, 1919.

Application filed January 31, 1918. Serial No. 214,607.

To all whom it may concern:

Be it known that I, FRANK J. HUMMEL, a citizen of the United States, residing at Pittsburgh, in the county of Allegheny and State of Pennsylvania, have invented certain new and useful Improvements in Toy Railways, of which the following is a specification.

My invention relates to toy railways, and to signaling apparatus and car controlling apparatus for use in connection with such railways.

I will describe one form of railway embodying my invention, and will then point out the novel features thereof in claims.

The accompanying drawing is a diagrammatic view showing one form of railway embodying my invention.

Referring to the accompanying drawing, the reference characters R, R' designate the track rails of a railway, between which rails is a third rail T. The railway is divided into blocks A—B, B—C, etc., in any suitable manner, this division being accomplished by means of insulations or breaks 2 in the third rail T. The third rail is further divided by insulations or breaks 2^a within each block to form a main section extending through the greater part of the block, and a short insulated section at the exit end of the block. Thus the main section of the third rail for block A—B is the section A—a, and the short insulated section at the exit end of this block is the section a—B.

Located adjacent the entrance end of each block is a signal which is designated by the reference character S with an exponent corresponding to the location of the signal, the signal at point A, for example, being designated S^a. Each of these signals comprises two lamps G and R, colored green and red respectively, each signal indicating "clear" when the green lamp is illuminated, and "danger" when the red lamp is illuminated.

Each block is provided with a relay for controlling the signal for the block, each of these relays being designated by the reference character N, with the same exponent as that of the signal which it controls. Each relay includes a contact 5 for controlling the corresponding signal, the circuits being so arranged that the green lamp G is illuminated when the relay is deenergized, and the red lamp R is illuminated when the relay is energized. The circuit for the green

lamp G of signal S^B, for example, is from a battery P through line wire 3, wire 4^B, back point of contact 5 of relay N^B, wire 6, lamp G, wire 7^B, line wire 8 to battery P. The circuit for lamp R of this signal is the same except that it includes the front point of contact 5 of relay N^B and wire 9 instead of the back point of this contact and wire 6.

One terminal 10 of relay N^B is constantly connected with the main third rail section 65 of block B—C by means of wire 11. The other terminal of this relay is connected with line wire 8 through wires 12 and 7^B. Line wire 3 is connected with the track rail R by a wire 13^B. It will be seen, therefore, that the battery P is connected across rail R and section B—b of the third rail T, and that this connection includes relay N^B. If, then, rail R and section B—b of rail T are electrically connected, relay N^B will be energized. Terminal 10 of relay N^B is also connected with the short section b—C of third rail T at the exit end of block B—C, but this connection is controlled by a contact 14 of relay N^C in such manner that the connection is direct or includes a resistance 15^C according as relay N^C is deenergized or energized. This connection, when relay N^C is deenergized, is from terminal 10 of relay N^B through wire 16, back point of contact 80 14 of relay N^C, wire 17 to third rail section b—C. When relay N^C is energized, this direct connection is broken and the connection passes through resistance 15^C and the front point of contact 14 of relay N^C. It follows, 90 then, that battery P is connected across third rail section b—C and rail R, this connection including relay N^B, but that when relay N^C is energized this connection also includes resistance 15^C.

Relay N for each block is connected with rails R and T for the block and with battery P in the same manner as is relay N^B.

Each car which travels along the railway is equipped with a traction motor M (see 100 car V), one terminal of which motor is connected with an axle of the car and so with track rail R, and the other terminal of which motor is connected with a brush 19 which makes contact with the third rail T. 105 The traction motor M is, therefore, constantly in a closed circuit including battery P and the relay N for the block which the car occupies. For example, when a car V is in section B—b of block B—C, the circuit 110

is from battery P through wires 3 and 13^B, rail R, axle of car V, motor M, brush 19, third rail T, wire 11, relay N^B, wires 12, 7^B and 8 to battery P. The current which flows in this circuit is of sufficient strength to operate motor M to drive the car, and also to energize relay N^B so that this relay causes signal S^B to indicate "danger." When the car is over the short insulated section at the exit end of block B—C, the circuit is from battery P through wires 3 and 13^B, rail R, wheel and axle of car V, motor M, brush 19, section b—C of third rail T, wire 17, back point of contact 14, wire 16, relay N^B, wires 12, 7^B and 8 to battery P. Current in this circuit likewise is of sufficient strength to operate the traction motor M and also to energize relay N^B. If, however, relay N^C is energized, resistance 15^C is included in the last traced circuit. This resistance reduces the current in the circuit to such value that it will not operate the traction motor M, but the current is still of sufficient strength to energize relay N^B so that signal S^B still indicates "danger."

The operation of the apparatus is as follows:

There being a car V in the block in advance of location C, relay N^C is energized so that signal S^C indicates "danger." Signals S^B and S^A, however, both indicate "clear." If now a second car, moving in the direction indicated by the arrow, enters block A—B, it will cause relay N^A to become energized, so that signal S^A will change from "clear" to "danger"; that is, the green lamp will be extinguished and the red lamp will become illuminated. As this second car enters the short third rail section at the exit end of block A—B, it continues to receive sufficient current to operate its traction motor, because relay N^B is deenergized. As the second car enters block B—C, it likewise causes signal S^B to change to "danger." Inasmuch as relay N^C is energized, resistance 15^C is included in the connection between third rail section b—C and relay N^B. Consequently, when the second car passes the point b, the current flowing through its traction motor is reduced to such value that this motor no longer operates. Hence the car comes to a stop in section b—C. Relay N^B, however, continues to be energized so that signal S^B continues to indicate "danger." As soon as the car V passes out of the block in which it is shown in the drawing, relay N^C will become deenergized, so that the second car, which is now assumed to be present in section b—C, will receive sufficient current to operate its traction motor, so that this car may then proceed into the block to the right of point C.

I will now assume that a car is at rest in the short section b—C at the exit end of

block B—C. Relay N^B will then be energized, so that resistance 15^B will be included in the circuit for section a—B. If, then, a second car should enter block A—B, it could proceed through the main section of this block, but would be brought to a stop upon entering the short exit section a—B because resistance 15^B would be included in the circuit of its traction motor.

It will thus be seen that when any part of a block is occupied by a car, a following car will be stopped upon entering the short section at the exit end of the block next in the rear.

Although I have herein shown and described only one form of railway and signaling system embodying my invention, it is understood that various changes and modifications may be made therein within the scope of the appended claims without departing from the spirit and scope of my invention.

Having thus described my invention, what I claim is:

1. A toy railway and signaling system comprising a track rail and a third rail, a source of current and a relay constantly connected in series across said track rail and said third rail, a car arranged to travel on said track rail and having means for electrically bridging said track rail and said third rail whereby it completes the circuit for said relay and energizes the latter, and a wayside signal controlled by said relay so as to indicate stop or proceed according as said relay is energized or deenergized.

2. A toy railway and signaling system comprising track rails, a third rail divided into sections to form blocks, a relay for each block, a partial circuit for each block including the corresponding relay and a source of current constantly connected in series across the corresponding third rail section and one of the track rails, a car adapted to travel on said track rails and having means for electrically bridging said third rail, and said one track rail whereby the relay for an occupied block is energized, and a wayside signal for each block controlled by the corresponding relay and arranged to indicate stop or proceed according as the relay is energized or deenergized.

3. A toy railway and signaling system comprising two conductors one of which is divided into sections to form blocks, and one of which conductors is a track rail and the other a third rail, a relay for each block, a partial circuit for each block including the corresponding relay and a source of current constantly connected in series across the corresponding divided conductor section and the other conductor, a car adapted to travel along said railway and having means for electrically bridging said two conductors whereby the relay for

an occupied block is energized, and a way-side signal for each block controlled by the corresponding relay and adapted to indicate stop or proceed according as the relay is 5 energized or deenergized.

4. A toy railway and signaling system comprising track rails, a third rail divided into blocks and having a short insulated section at the exit end of each block, signal 10 controlling means for each block having one terminal connected with the main section of the third rail, a source of current connected with the other terminal of each signal controlling means and a track rail, a resistance 15 for each block, means for each block controlled by the signal controlling means for the block in advance for connecting the first-mentioned terminal of the signal controlling means for the block directly with the short 20 third rail section at the exit end of the block or for inserting said resistance in such connection according as the block in advance is free or occupied, a car arranged to travel on said track, and a traction motor on said car 25 connected with said third rail and with the track rail to which said source of current is connected.

5. A toy railway and signaling system comprising two conductors with which the 30 cars make moving contact, at least one of which conductors is divided into blocks and further sub-divided to form a short insulated section at the exit end of each block, signal controlling means for each block having one terminal connected with the main divided conductor section for the block, means for each block for creating a difference of potential between the other terminal of each signal controlling means and the other said 35 conductor, means for each block controlled by the signal controlling means for the block in advance for connecting the first-mentioned terminal of the corresponding signal controlling means with the corresponding short divided conductor section either directly or through a resistance according as the block in advance is free or occupied, a car having contacts engaging with said two conductors respectively, and 40 a traction motor on said car connected with said contacts.

6. A toy railway and signaling system comprising two conductors with which the cars make moving contact, at least one of 45 which conductors is divided into blocks and further sub-divided to form a short insulated section at the exit end of each block,

signal controlling means for each block having one terminal connected with both of the divided conductor sections for such block, 60 means for each block for creating a difference of potential across the other conductor and the remaining terminal of the corresponding signal controlling means, and means controlled by each signal controlling 65 means and operative when a block is occupied for inserting a resistance between the short insulated conductor section of the block in the rear and the signal controlling means for such block in the rear, a car, 70 and a traction motor on the car connected with said two conductors.

7. A toy railway and signaling system comprising two conductors with which the cars make moving contact, at least one of 75 which conductors is divided into blocks and further sub-divided to form a short insulated section at the exit end of each block, a relay for each block having one terminal connected with both of the divided conductor 80 sections for the block, the said connection with the exit end section including a back contact of the relay for the block next in advance, a branch for each latter connection around the said back contact and including 85 a front contact of the same relay and a resistance, means for creating a difference of potential between the other terminal of each relay and the other said conductor, a car, a traction motor thereon connected with 90 said two conductors, and signals for the blocks controlled by said relays.

8. A toy railway and signaling system comprising two conductors with which the cars make moving contact, at least one of 95 which conductors is divided into blocks and further sub-divided to form a short insulated section at the exit end of each block, a car, a traction motor thereon connected with 100 said two conductors, a source of current connected across the two said conductors of each block, signal controlling means for each block included in said connections, and means for each block controlled by traffic conditions in advance for inserting a resistance in the connection between the source and the exit section of the divided conductor 105 for such block.

In testimony whereof I affix my signature in presence of two witnesses.

FRANK J. HUMMEL.
